UNITED STATES PATENT OFFICE.

JAMES CLARKE HAGEY, OF CHICAGO, ILLINOIS, ASSIGNOR TO THE CABLE COMPANY, OF CHICAGO, ILLINOIS, A CORPORATION OF ILLINOIS.

METHOD AND APPARATUS FOR PREPARING MUSIC ROLLS.

Application filed August 29, 1919. Serial No. 320,589.

My invention relates to the preparation of music-rolls.

One important use of my invention is in connection with the production of "hand-played" music-rolls. A "hand-played" roll is a roll which is designed for use with an automatic musical instrument to reproduce the rendition of a musical composition as played by an artist. In the production of such rolls, it has been customary to use a recording-device which will automatically make a record showing which notes were played and the duration of these notes. It has also been attempted to make a record of the piano-key dynamics, for the purpose of obtaining a record of the tonal volume or power of the individual notes.

One of the objects of my invention is to provide an improvement in the art of securing a record of the tonal characteristics of the notes, such as the tonal volume thereof, in connection with the securing of the record of the other qualities of the notes (such as pitch, duration, etc.), the complete record thus secured being used in the production of "hand-played" music-rolls.

A further object of my invention is to provide a novel and improved method of preparing a music-roll, which method includes, as a step therein, providing the music-roll with means for controlling the tonal characteristics of the notes, such as the tonal volume thereof, as indicated in a record obtained from an actual rendition of the musical selection, whether or not such record be obtained in the manner or by the apparatus herein set forth.

In order to give a general idea of the invention, it is here stated that, in the embodiment of my invention shown, sound-vibration-controlled means are employed for making a record of the tonal characteristics of the notes sounded, at the same time that key-controlled markers are used for making a record which will show the pitch and duration of the notes sounded.

In one embodiment of my invention, a sound-vibration-controlled recording-mechanism is provided which will record the tonal characteristics, including the tonal volume, of each individual note. In another embodiment of my invention, a sound-vibration-controlled recording-mechanism is used which will not record the tonal characteristics of each individual note, but which

will make a record which might be called a record of the composite tonal volume of all of the notes simultaneously sounded.

In both forms of my invention, the mechanism for recording the tonal characteristics is used in connection with a mechanism for recording the pitch and duration of the notes.

In the drawings, in which two embodiments of my invention are shown:

Fig. 1 is a view showing a side elevation of a grand piano and the recording-device used in connection therewith, parts being broken away and parts shown in section;

Fig. 2 is a view, similar to Fig. 1, showing another form of recording-device;

Fig. 3 is a plan view of part of the recording-device shown in Fig. 2.

Referring now to the drawings in detail, and first to the form of my invention shown in Fig. 1, the construction there shown comprises a grand piano 10 and a recording-device 11. The grand piano may be located in one room and the recording-device in another. The recording-device 11 comprises mechanism 12 for making a record which will show the pitch and duration of the notes sounded, and mechanism 13 which will make a record of the tonal characteristics of the individual notes sounded.

The mechanism 12, for recording the pitch and duration of the notes sounded, may be of any usual or suitable construction, the one I have shown comprising a plurality of vertically reciprocable markers or pencils 14 and a plurality of pneumatic-actuators 15, one for each of the markers 14. There is one pneumatic-actuator for each key of the piano 10. Each pneumatic-actuator 15 may

be controlled from the corresponding piano-key 16 by means of a valve 17, located beneath the corresponding key 16 and controlling a port 18, from which a conduit 19 leads to a controlling-valve-mechanism for controlling the action of the respective pneumatic-actuator 15. The valve 17 may be a leaf-spring-valve, normally held in position to close the port 18 by its spring tension. When the key 16 is depressed, the valve 17 is opened by means of a plunger 20, slidably mounted in the key-bed 21 and extending between the valve 17 and its corresponding key. This construction is more or less diagrammatically shown, and is subject to considerable variation and refine-

110

ment, in actual use, to permit a suitably responsive action of the markers 14 without interfering with the "touch" of the piano-keys. The construction is such that, when 5 the mechanism 12 is provided with air-tension, supplied from any suitable source (not shown), and the piano-key 16 is depressed, the corresponding pencil or marker 14 will be depressed and will be held down as long 10 as the key is held down.

A record-blank 22 is caused to travel beneath the markers 14 by means of a suitable record feeding mechanism 23. When the recording-mechanism 12 is in operation 15 and the record-blank travels underneath the markers, the markers, when depressed, will make lines on the record-blank, the length of which lines will correspond to the duration of the notes, and the position of which 20 will indicate which piano-key was depressed, and will thus indicate the pitch of the corresponding note.

The mechanism 13, for recording the tonal characteristics of the notes sounded, may 25 be a dictaphone or similar device, provided with a receiving-horn 24, the larger end of which may be located underneath the sounding-board 25 of the piano. This receiving-horn leads to the sound-box 26 of the dictaphone. A valve or damper 27^a may be located in the passage, at the smaller end of the receiving-horn 24, for modifying the sound-vibrations. This damper may be provided with a handle 27^b located in a position 30 convenient for the person who has charge of the recording-mechanism. Suitable indicating-means 27^c may be provided for indicating the position of the damper. The indicating-means 27^c, as shown, is provided with the letters L, M and S, indicating 35 "loud," "medium" and "soft". If the artist employs what the operator considers to be a heavy touch, the damper is moved to the position indicated as "loud". This restricts 40 the passage in the receiving-horn and lessens the effect of sound-vibrations on the record.

This record is used with a reproducing machine (not shown) in editing music-rolls. This reproducing machine is provided with 45 a damper, which damper can be set at various positions, indicated as "loud", "medium" and "soft". When a record, which has been marked as a "loud" record, is used with the reproducing machine suggested, the damper 50 of the reproducing machine is set at "loud", so that the reproduction rendered by the reproducing machine will correspond to the original rendition. Similarly, if the artist employs what the operator considers to be 55 a medium touch, the indicating-means 27^c may be moved to the position indicated as "medium". The record thus made is marked as a "medium" record. When this record is placed on the reproducing machine suggested, the damper of this reproducing machine 60

is moved to "medium" position, so that the reproduction of this "medium" record will also correspond to the original rendition.

A similar use of the damper 27^a and the damper of the suggested reproducing machine is made, if the artist has what the operator considers to be a light touch.

When the piano is played and the recording-mechanism 13 is in operation, the sound-vibrations, corresponding to the notes 75 sounded, cause the diaphragm of the sound-box 26 to vibrate and to record, on the wax cylinder 27^d, the tonal characteristics, including the volume of power, of the individual notes.

Applicant is, of course, aware that sound-vibration-controlled means have been employed for making a record of musical renditions. He does not, however, believe that sound-vibration-controlled means have been 85 used for making a record of the tonal characteristics, in connection with means for making a record showing which of the note-sounding devices were actuated.

The operation of the device has been outlined in connection with the description of the structure. In operation, the artist renders a selection on the piano 10, the recording-device being put into operation to make a record of this rendition. The recording-mechanism 12 will make a record on the record-blank 22, indicating which keys of the piano were struck, the relative time at which they were struck, and the length of time they were held down. At the same time, the tonal-characteristics recording-mechanism 13 will make a record on the wax cylinder 27^d of the tonal characteristics of the individual notes sounded.

After the records are made by the recording-mechanisms 12 and 13, they may be used in the preparation of a master-sheet. This master-sheet may be used to produce hand-played music-rolls which, when used with a suitable automatic musical instrument, will 100 effect the rendition of a musical selection in the manner in which it was originally rendered by the artist, not only with respect to pitch and duration of notes, but also with respect to tonal characteristics, including the 105 tonal volume and delicate "colorings" or "shadings". The tone-characteristics record, made by the recording-mechanism 13, may also be used as a guide in placing a "dynamic-line" on a music-roll, which 110 "dynamic-line" will indicate to the person using the music-roll the proper tonal volume to be produced. To explain further the two uses suggested: the records made by the recording-mechanisms 12 and 13 may 115 be used in the preparation of a master-sheet which may be used to produce a music-roll such as will, when used with a suitable automatic musical instrument, automatically 120 effect the rendition of the selection as origi- 125 130

nally played by the artist, reproducing the pitch, relative arrangement, and duration of the notes, and giving the proper tonal characteristics including the volume and "coloring" or "shadings"; or the record produced by the recording-mechanism 12 may be used in the production of a music-roll which will automatically control the rendering of the selection, insofar as giving the notes the same pitch, relative arrangement, and duration, as in the original rendition, and the record made by the recording-mechanism 13 may be used in placing on this music-roll a "dynamic-line", which will enable the person using the music-roll to control the instrument in a way to give the notes the same tonal volume as was given in the original rendition. By the use of this method of simultaneously recording note relationship, occurrences and duration, as well as the tonal characteristics given such notes, a music-roll may be prepared by one who did not even hear the artist's original rendition, and who was not in the least acquainted with the artist's style of playing, and this music-roll may be used, in connection with a suitable automatic musical instrument, to faithfully reproduce the artist's individual style of playing and his peculiar interpretation of the composition, including accurate phrasing and the most delicate "tone-coloring" or "shading".

In the use of my invention shown in Fig. 2, the piano 10, the recording-mechanism 12, and the means for controlling the recording-mechanism 12 from the keys of the piano, may be substantially the same as in the form previously described. In Fig. 2, however, the receiving-horn 24 leads to a recording-mechanism 28 which makes a visible record. This recording-mechanism 28 comprises a sound-box 29, which may be similar to the sound-box on a dictaphone, and a marker 30, pivotally mounted at 31 and pivotally connected at 32 to the diaphragm of the sound-box 29. The amplitude of vibration of the marker 30 will correspond to what may be called the composite tonal volume of the rendition of the musical selection on the piano 10. The marker 30 may make a visible record on the same record-blank as that on which the markers 14 make their record.

The use of this form of recording-device is similar to the use of the form previously described. The recording-mechanism 12 operates, during the rendition of a selection on the piano 10, to make a record showing which of the keys were depressed and how long they were depressed, and the tonal-volume-recording-mechanism 28 operates to make a record showing the tonal volume. The records made by the two recording-mechanisms may be used to produce a music-roll which will automatically give the same

rendition as the artist's original playing as to pitch, occurrences, duration, and tonal volume of the notes; or the record made by the recording-mechanism 12 may be used in the production of a music-roll which will automatically cause the same notes to be sounded as were sounded in the original rendition, and the record made by the recording-mechanism 28 may be used in placing a "dynamic-line" on the music-roll, to enable the operator, by following it in his manipulation of suitable controlling-devices, to give the proper tonal volume to the rendition on an automatic musical instrument.

It is probably well here to refer to the well-known fact that the degrees of tonal volume are produced upon a piano by manipulating the piano-keys with more or less power and by the use of suitable piano-pedals. "Hand-played" music-rolls are usually provided with pedal-controlling perforations, in addition to the note-perforations, and the recording-mechanism 12 of my device is provided with one or more pneumatic-actuators 15 which are controlled in operation, individually, by one or more of the piano-pedals in substantially the same manner as I have shown in connection with a piano-key, the resultant mark upon the record-blank 22 indicating when, and for how long, the respective piano-pedal was operated. The records made by the recording-mechanisms 13 and 28 are, primarily, records of tonal characteristics, and embody the effects produced by the artist's operation of the piano-pedals, as well as the piano-key dynamics, or the power with which the artist manipulated the piano-keys. In preparing the "hand-played" music-rolls, the music-roll-blank is first prepared with note-controlling and pedal-controlling perforations, according to the record made by the recording-mechanism 12, and the music-roll thus prepared is then played upon a suitable automatic musical instrument. The notes are sounded in proper order and length and the piano-pedals are operated, all as originally performed by the artist. It remains to apply, in or upon the music-roll, volume-controlling or volume-indicating characters, which may be in the form of perforations (or some other means for controlling the automatic operation of mechanical devices in the particular automatic musical instrument with which the music-roll may be designed for use) or in the form of instructions or means, such as the "dynamic-line" or "expression-line," for indicating, to the operator of the automatic musical instrument, the key-dynamics, or the relative degrees of power that should be exerted in playing. These volume-controlling or volume-indicating characters, whether in the form of perforations, or lines, or other forms, actually represent (in percussion

instruments, such as a piano) the degrees of power to be applied in the sounding of the notes, which means key-dynamics. My invention, therefore, embraces the 5 method of preparing music-rolls which comprises obtaining a record of the tonal characteristics of the rendition of the musical composition and then so applying that record in or upon a music-roll that it 10 will properly represent, with relation to the note-perforations, the key-dynamics, or the power to be applied, as well as other tonal characteristics to be produced in the sounding of the notes.

5. The term "tonal characteristics", as employed herein, is to be understood as meaning such characteristics as are recorded in and reproducible from a sound-record.

What I claim as new and desire to secure 20 by Letters Patent of the United States, is:

1. The combination with a musical instrument comprising a plurality of selectively controllable note-sounding units, of recording-means comprising means for making, at 25 the time the selection is being rendered, a record showing which of the note-sounding units were actuated, and sound-vibration-controlled means for making a record of the tonal characteristics of the notes sounded at 30 the time the selection is rendered.

2. The combination with a musical instrument having a plurality of selectively controllable note-sounding units, of recording-means comprising means for making, at the 35 time the selection is rendered, a record showing which of the note-sounding units were actuated, and sound-vibration-controlled means for making a record of the tonal characteristics of the individual notes sounded.

40 3. A machine for recording a rendition of a musical selection as it is rendered on an instrument having a plurality of selectively controllable note-sounding units, comprising means for making, at the time the selection 45 is rendered, a record showing which of the note-sounding units were actuated, and sound-vibration-controlled means for making a record of the tonal characteristics of the rendition.

50 4. A machine for recording a rendition of a musical selection as it is rendered on an instrument having a plurality of selectively controllable note-sounding units, comprising means for making, at the time the 55 selection is rendered, a record showing which of the note-sounding units were actuated, and sound-vibration-controlled means for making a record of the tonal characteristics of the individual notes.

60 5. A machine for recording a rendition of a musical selection as it is rendered on an instrument having a plurality of selectively controllable note-sounding units, comprising means for making, at the time the selection 65 is rendered, a record showing which of the

note-sounding units were actuated, and sound-vibration-controlled means for making an audibly reproducible record of the tonal characteristics of the rendition.

6. A machine for recording a rendition of 70 a musical selection as it is rendered on an instrument having a plurality of selectively controllable note-sounding units, comprising means for making, at the time the selection is rendered, a record showing which of the 75 note-sounding units were actuated, and sound-vibration-controlled means for making an audibly reproducible record of the tonal characteristics of the individual notes.

7. The method of preparing a music-roll 80 by producing thereon expressions of pitch and time note-valuation, which expressions represent the notes of a musical selection, and providing said music-roll with means for controlling tonal volume; which method comprises the employment of a sound-record of the same musical selection as a guide for determining the proper arrangement of said means upon said music-roll with respect to 85 said expressions of pitch and time note-valuation thereon.

8. The method of preparing a music-roll 90 by producing thereon expressions of pitch and time note-valuation, which expressions represent the notes of a musical selection, and providing said music-roll with means for controlling tonal volume; which method comprises ascertaining, from a sound-record of the same musical selection, the tonal volume to be given the notes of said selection 100 and arranging said means upon said music-roll, with respect to the said expressions of pitch and time note-valuation thereon, to control the tonal volume of the notes so expressed in accordance with the variations 105 in the tonal volume of said notes as ascertained from said sound-record.

9. The method of preparing a music-roll 110 by first producing upon a sheet expressions of pitch and time note-valuation, which expressions represent the notes of a musical selection, and thereafter providing said sheet with expressions of tonal volume; which method comprises the employment of a sound-record of the same musical selection 115 as a guide for determining the proper arrangement of said expressions of tonal volume upon said sheet with respect to said expressions of pitch and time note-valuation thereon.

10. The method of preparing a music-roll 120 by first producing upon a sheet expressions of pitch and time note-valuation, which expressions represent the notes of a musical selection, and thereafter providing said sheet with expressions of tonal volume; which method comprises ascertaining, from a sound-record of the same musical selection, the tonal volume to be given the notes of 125 said selection and arranging said expres- 130

sions of tonal volume upon said sheet, with respect to the said expressions of pitch and time note-valuation thereon, to serve in controlling the tonal volume of the notes so expressed in accordance with the variations

5 in the tonal volume of said notes as ascertained from said sound-record.

11. The method of preparing a music-roll by making perforations therein expressing

10 pitch and time note-valuation, which perforations represent the notes of a musical selection, and providing said music-roll with expressions of tonal volume; which method comprises the employment of a sound-record

15 of the same musical selection as a guide for determining the proper arrangement of said expressions of tonal volume upon said music-roll with respect to said perforations.

12. The method of preparing a music-

20 roll by making perforations therein expressing pitch and time note-valuation, which perforations represent the notes of a musical selection, and providing said music-roll with expressions of tonal volume; which method

25 comprises ascertaining, from a sound-record of the same musical selection, the tonal volume to be given the notes of said selection and arranging said expressions of tonal volume upon said music-roll, with respect to

30 said perforations therein, to serve in controlling the tonal volume of the notes represented by said perforations in accordance with the variations in the tonal volume of said notes as ascertained from said sound-

35 record.

13. The method of providing a music-roll, having perforations therein which constitute expressions of pitch and time note-valuation and represent the notes of a musical

40 selection, with expressions of tonal volume; which method comprises the employment of a sound-record of the same musical selection as a guide for determining the proper arrangement of said expressions of tonal

45 volume upon said music-roll with respect to said perforations.

14. The method of preparing a music-roll, having perforations therein which constitute expressions of pitch and time note-

50 valuation and represent the notes of a musical selection, consisting of providing it with means for controlling the tonal volume of the notes so expressed and represented as ascertained from a phonograph record of

55 the same musical selection.

15. The method of preparing a music-roll by producing thereon expressions of pitch and time note-valuation, which expressions represent the notes of a musical selection,

60 and providing said music-roll with means for controlling the tonal characteristics of the notes so expressed; which method comprises the employment of a sound-record of

65 the same musical selection as a guide for determining the proper arrangement of said

means upon said music-roll with respect to said expressions of pitch and time note-valuation thereon.

16. The method of preparing a music-roll by producing thereon expressions of pitch

70 and time note-valuation, which expressions represent the notes of a musical selection, and providing said music-roll with means

75 for controlling the tonal characteristics of the notes so expressed; which method com-

prises ascertaining, from a sound-record of

the same musical selection, the tonal characteristics to be given the notes of said selec-

80 tion and arranging said means upon said

music-roll, with respect to the said expres-

85 sions of pitch and time note-valuation there-

on, to control the tonal characteristics of the

notes so expressed in accordance with the

variations in the tonal characteristics of said

notes as ascertained from said sound-record.

17. The method of preparing a music-roll by first producing upon a sheet expressions

of pitch and time note-valuation, which ex-

pressions represent the notes of a musical

selection, and thereafter providing said

sheet with expressions of tonal characteris-

tics; which method comprises the employ-

ment of a sound-record of the same musical

selection as a guide for determining the

proper arrangement of said expressions of

tonal characteristics upon said sheet with re-

spect to said expressions of pitch and time

note-valuation thereon.

18. The method of preparing a music-roll by first producing upon a sheet expressions

of pitch and time note-valuation, which ex-

pressions represent the notes of a musical

selection, and providing said music-roll with

means for controlling the tonal characteristics

pitch and time note-valuation, which perforations represent the notes of a musical selection, and providing said music-roll with expressions of tonal characteristics; which 5 method comprises ascertaining, from a sound-record of the same musical selection, the tonal characteristics to be given the notes of said selection and arranging said expressions of tonal characteristics upon 10 said music-roll, with respect to said perforations therein, to serve in controlling the tonal characteristics of the notes represented by said perforations in accordance with the variations in the tonal characteristics of said 15 notes as ascertained from said sound-record.

21. The method of providing a music-roll, having perforations therein which constitute expressions of pitch and time note-valuation and represent the notes of a musical

selection, with expressions of tonal characteristics; which method comprises the employment of a sound-record of the same musical selection as a guide for determining the proper arrangement of said expressions of tonal characteristics upon said music-roll 25 with respect to said perforations.

22. The method of preparing a music-roll, having perforations therein which constitute expressions of pitch and time note-valuation and represent the notes of a musical 30 selection, consisting of providing it with means for controlling the tonal characteristics of the notes so expressed and represented as ascertained from a phonograph record of the same musical selection. 35

In witness whereof, I have hereunto subscribed my name.

J. CLARKE HAGEY.
